UNITED STATES PATENT OFFICE.

ANSON F. BARTON, OF DEDHAM, MASSACHUSETTS.

IMPROVEMENT IN STEAM-BOILERS.

Specification forming part of Letters Patent No. 40,016, dated September 22, 1863.

To all whom it may concern:

Be it known that I, ANSON F. BARTON, a resident of Dedham, in the county of Norfolk and State of Massachusetts, have made an invention of a new and useful Improvement in Steam Boilers or Generators; and I do hereby declare the same to be fully described in the following specification, and represented in the accompanying drawings, of which—

Figure 1 is a longitudinal section of a furnace and a boiler thereof, the latter being made in accordance with my invention. Fig. 2 is a transverse section of the same.

The nature of my invention consists in an improved boiler or steam-generator as constructed with a smoke passage or flue and a crescent-shaped addition or water-vessel, combined and arranged with a main cylinder or boiler, substantially in manner and so as to operate as hereinafter specified.

In the drawings, A denotes the brick-work for supporting the boiler and its addition, while B is the furnace, C the grate, and D the ash-pit. The furnace is arranged directly underneath the front third part of the main portion E of the boiler, which is a hollow cylindrical vessel, and may be provided with a series of smoke flues or tubes extending through it longitudinally and opening out of each end of it.

To opposite sides of the boiler and extending underneath it, in the crescent form, as shown in Fig. 2, is affixed an auxiliary boiler or water vessel, F, which at its junctions with the cylindrical boiler has openings *a a* leading into it, each of such openings being situated both above and below the water-line of the said part E. The length of this crescent-shaped vessel is to be about two thirds that of the vessel or boiler E, and the two vessels are also to be connected by a pipe, G, leading from the rear end of one into the rear end of the other

and close to their bottoms. There is arranged between the vessels E and F a smoke-passage, H, which is to lead the smoke from the fire-place or furnace and longitudinally between the two vessels, the same being in order to heat both vessels by the same column of smoke. When the boiler and its auxiliary vessel are supplied with water, and heat is applied to them to heat such water and produce steam, there will be a free circulation through the two vessels.

If desirable the auxiliary vessel may be arranged directly over the furnace, so that the heat thereof may act directly on its bottom surface, and thence pass back through the intermediate flue, and not only heat the under surface of the main boiler, but the top or upper surface of the auxiliary water-vessel or boiler.

In Fig. 1 of the drawings, the smoke is exhibited as passing from the passage H into a chamber or flue, I, and thence through the tubes *b b b* of the main boiling-vessel E and into a chamber, K, at the front thereof. Out of this chamber the smoke passes into an escape pipe or flue.

By means of the auxiliary water-vessel F, combined and arranged with the main boiler E and the flue H, as described, much of the heat, that is frequently absorbed by the brick-work and lost, can be employed to advantage in the generation of steam.

I claim—

The improved steam-generator as constructed with the smoke-flue H and the crescent-shaped water-vessel F, combined and arranged with the main boiler E, substantially in manner and so as to operate as specified.

ANSON F. BARTON.
